CLAIM

(**) Term: **14 Years**

(21) Appl. No.: **29/127,587**

The ornamental design for an armband with physiological monitoring system, substantially as shown and described.

(22) Filed: **Aug. 9, 2000**

DESCRIPTION

(51) LOC (7) Cl. **24-01**

FIG. 1 is a front isometric view of an armband with physiological monitoring system, showing our new design;

(52) U.S. Cl. **D24/186**

FIG. 2 is a bottom plan view thereof;

(58) Field of Search D24/186; 600/300,

600/301, 322, 323, 388, 483, 519, 534,

536, 544

FIG. 3 is a top plan view thereof;

FIG. 4 is a front elevational view thereof;

FIG. 5 is a rear elevational view thereof;

FIG. 6 is a side elevational view thereof; and,

FIG. 7 is a side elevational view thereof, opposite that shown in FIG. 6.
